UNITED STATES PATENT OFFICE.

ANDREW J. BOHNENGEL, OF TOLEDO, OHIO.

NOTATION-STRIP MANUFACTURE.

Application filed November 2, 1925. Serial No. 66,430.

This invention relates to forming and marking strip material.

This invention has utility when incorporated in measuring notation carrying strips, especially as adapted for handling strip stock, as ribbons, with overage for central anchoring and outer wrapping.

Referring to the drawings:

Fig. 1 is a side elevation, with parts broken away, showing an embodiment of the invention incorporated for a multiple range, as well as multiple transverse width strips;

Fig. 2 is an end elevation of the machine of Fig. 1 from the supply or right hand end 15 of the machine of Fig. 1;

Fig. 3 is a detail view of features of the speed reduction or intermittent drive for controlling an indication or rotation marking herein applied as for terminal signal;

Fig. 4 is a section adjacent the gear through the carrier as having the drive shown in Fig. 3;

Fig. 5 is a plan view, with parts broken away, of the machine of Fig. 1;

Fig. 6 is a diagram of the stock travel and the co-operative elements for notation and slitting, as well as receiving such treated strips;

Fig. 7 is a section on the line VII—VII, 30 Fig. 2, showing a notation carrier disk;

Fig. 8 is a side elevation of a portion of these disks as mounted on adjacent shafts of the carrier;

Fig. 9 is a view of a pair of the rotary 35 knives, one being shown in section and the other in elevation;

Fig. 10 is a side view of one of the knives;

Fig. 11 is a view of the speed reduction 40 drive as a transmission from the machine drum;

Fig. 12 is a detail view of the disconnector pawl of this transmission for re-set;

Fig. 13 is a fragmentary view of a wound strip showing the lineal notation and the 45 signal marking;

Fig. 14 is a view showing a portion of the strip as the completion of the preceding notation cycle with the clearance or overage therefrom to the succeeding or initiation of 50 the following cycle or notation marking;

Fig. 15 is a diagram of the cycle notation for quarter of a yard measurements of a ten-yard cycle with the overage gap provision;

Fig. 16 is a tabulation of the notation 55 cycle in one-half yard steps for a fifty-yard measurement with overage;

Fig. 17 is a partial section on the line XVII—XVII, Fig. 1.

Stock travel.

60

General machine frame 1 is shown as having brackets 2 (Figs. 1, 5) extending outward from the supply end to provide sustaining bearings 3 in which may be disposed shaft 4 carrying roll of stock 5, say as a 65 strip of paper, of a considerable width, as coming from the paper mills. This shaft 4 is clamped in the bearing 3 by bearing members 6 having pivotal mounting 7 in the bracket 2. Bolts 8 adjust the clamping of 70 these bearing members 6 with the bearing members 3, as a frictional retarder or brake for the wide strip of material 9 as being unwound from the roll of paper 5. This strip of material 9 passes under roller 10, thence 75 about idle roller 11 mounted in bracket 11' of the machine frame 1, and back about drum 12 where it is held snugly in contact with the drum 12 by the roller 10. This roller 10 precludes crowding or over-running 80 of the paper on the drum 12. This roller 10 is mounted by angle lever 13 in bearing 14 and has its holding action adjusted by screw 15, as locked by nut 16.

In the operations hereunder, the measuring is effected directly by the travel positions of the stock over the drum 12 (Fig. 6). Accordingly, it is important as to the gauge of the sheet material to have the drum 12 periphery built up say with make-ready 85 17 90 for maintaining the desired backing and diameter for the paper stock as held against the drum 12 for a large arc of contact from the roller 11, past the roller 10, thence about roller 18. The drum 12 is the region 95 of the strip material receiving marking or notation impressions and such of these as are of ink, are given a blotting action at roller 19 by blotting roller 20. The full width of stock 9, as thus bearing the notation, passes from this pair of rollers 19, 20, to travel between shafts 21, 22, carrying the knives or slitters. The stock is then divided up into a plurality of strips of the desired widths and passes between guide rollers 23, 100 24, and is alternately passed up and down for adjacent strips so that strip 25 passes downwardly from the guide roller 23, while adjacent strip 26 (Figs. 1, 6) passes upwardly therefrom. The strip 25 is wound 105 up upon receiving shaft 27 as the strips 26 are spaced along from each other and wound

upon receiving shaft 28. Gravity bar 29 resting on the strips 26, as passing from between the rollers 23, 24, is a factor against recoil in any stopping of the machine. 5 This bar is of metal and in the operation of the machine, there seems to be a tendency to develop electric charge in the stock, and this bar, as a conductor connector, eliminates trouble from static discharges.

10

Machine drive.

From a motor, line shaft, or other source of power, there may extend driving belt 30 about loose pulley 31 on shaft 32 (Figs. 1, 15 2, 5). For driving operation, belt shifter 33 is operated to shift this belt 30 from the loose pulley 31 to the fast or driving pulley 34 fast on the shaft 32, which shaft 32 carries the guide roller 18. This shaft 32 has 20 fast thereon pinion 35 in mesh with gear 36 (Fig. 6) for rotating the drum 12. This gear 36 is also in mesh with gear 37 on shaft 38. This gear 37 is in mesh with pinion 39 actuating gear 40 for driving the roller 19. 25 Also in mesh with this gear 37 is gear 41 in mesh with gear 42 on knife carrying shaft 21. This gear 42, is in mesh with gear 43 on knife carrying shaft 22. It is, accordingly, seen that the notation or impression receiving drum 12, the guide roller 18, the guide roller 19, and the knife carrying shafts 21, 22, are directly, positively, continuously driven.

35

Inking drive.

The drum 12 is mounted on shaft 44 carried by the frame 1 (Fig. 1). This shaft 44 has pinion 45 in mesh with gear wheel 46 having wrist pin 47 coacting through connecting rod 48 extending as a link to short arm 49 on angle lever having fixed fulcrum 50 carried by the frame 1. Upwardly extending from this fixed fulcrum 50, there is long arm 51 of this angle lever 49, 51. The 45 upper free end of this angle lever 51 is provided with fork 52 in which is disposed inking supply roller 53 coacting with inking fountain roller 54 in ink carrying trough 55 mounted by bracket 56 to upwardly extend 50 from the frame 1. In the rotation of the gear 46 on fixed bearing 57, mounted in the frame 1, the wrist pin 47 is effective for rocking angle lever 49, 51, to such an extent that ink transferring roll 53 may be shifted 55 from the ink fountain roll 54 to iron drum 58 mounted in bearings 59.

The gear 36, fixed with the drum 12, is in mesh with gear 60 on shaft 61 carried by the frame 1. This shaft 61 has fixed thereon 60 sprocket wheel 62 having sprocket chain 63 extending upward therefrom about sprocket wheel 64 on the shaft 59'. Accordingly, as the drum 12 rotates to rock the angle lever 49, 51, to deliver ink from the ink fountain 65 to the drum 58, this drum 58 is rotated

through the sprocket gearing and has the ink, as delivered thereto by the roller 53, spread by ink spreader composition roll 65 mounted in bearing 66 carried by bracket 67 from the frame 1. Additionally, coacting 70 with this roll or drum 58, as adjusted by screw 68 coacting with bearings 69 in guides 70 for shaft 71, there is transfer roll 72 which coacts with the drum 58 for delivering ink to notation or marking means herein 75 shown as signal markers 73, 74, on carrier 75, having the gear 60 as continuous rotation means therefor from the drum 12.

Supplemental ink delivery occurs from the fountain roll 54 alternately with the action of the roll 53. The arm 51 carries pin 76 loosely coacting with block 77 having telescopic coaction with stem 78 about which is tension spring 79 adjusted by nut 80 at head 81 coacting with pin 82 on arm 83 85 mounted in bearings 84 carried by the frame 1. There is, accordingly, provided an extensible link for effecting yieldable throwing of the arm 83 simultaneously with the throwing of the arm 51. This arm 83, at its 90 upper or free end, has fork 52 for ink transfer roll 53 effective in the swinging of the arm 83 for contacting ink fountain roll 54 as the arm 51 brings the roll 53 to contact with the inking drum 58. As the roll 53, 95 on the arm 83, has received ink from the roll 54, it swings back to contact inking drum or roll 85 mounted on shaft 86 carried by the frame 1. This shaft 86 has sprocket wheel 87 (Fig. 1) about which extends 100 sprocket chain 88 from sprocket 89 on the shaft 59' adjacent the sprocket wheel 64. Accordingly, simultaneously with the rotation of the inking drum 58, there is rotation 105 of the inking drum 85. Ink spreader roll 65, in bearings 90, coacts with the drum 85. Adjusting screws 68 coact with bearing blocks 69 in guides 70 for adjusting shafts 71 as carrying transfer rolls 91, 92. The transfer roll 91 coacts with notation lineal 110 marking means herein shown as for cycle production, as type 93, while for different lineal cycle, type 93 are contacted by the transfer roll 92 (Fig. 6).

Ten-yard notation cycle.

The type 93 are mounted in seats 94 of disks 95 to be held in position by bolts 96 coacting with clamping plates 97. These disks 95 are keyed against rotation as to 120 shafts 98 by key 99 (Fig. 7). The position of the respective disks longitudinally of the shafts 98, is determined by set screws 100. These shafts 98, in the instance shown, are grouped in a carrier 101 at equal spacings 125 of 60° . This carrier 101 is provided with teeth 102 in mesh with the gear 36 of the drum 12. In the rotation of the drum 12, it follows there is continuous similar lineal speed rotation of the gear teeth 102. Each 130

of these shafts 98 (Figs. 1, 6) carries a star-wheel 103. Fast with the frame 1, coaxial with shaft 104 mounting the carrier 101 and the gear 102, is disk 105 carrying a single tooth 106 coacting as a long tooth with the star wheels 103 in the two planes, as these star wheels slightly overlap and end their mountings on the shafts 98. Accordingly, in each rotation of the carrier 101, there is a step-up of one tooth in the rotation of each of the star wheels 103, and, accordingly, a presentation to the drum 12 of a succeeding notation or type 93 for giving impression to the strip material 9 as passing over this drum 12.

The notation cycle, as disclosed for this carrier 101, is for ten yards with quarter yard notations. On this basis, the disks are each provided with spacings approximating one-seventh of a circumference, and as to this carrier, these spacings are complete as to five thereof, and as to six positions on the sixth. This provides a starting point for the initial notation and leaves a blank intermediate from the final notation of the preceding cycle as completion of ten yards. This means that between the ten-yard notation and the zero notation, there is a one-half yard of overage. In the cutting of this strip material, there may be enough of this one-half yard, as portion 107 (Fig. 14) left with the zero for adherence to the spool upon which the stock is wound before the beginning of the stock with severing mark 108 leaving an overage 109 beyond the ten yards for wrapping beyond the end of the completed stock.

Fifty-yard notation cycle.

In the machine of this disclosure, there is range for adaptation so that the machine may be mixed in its production instead of run for a single character of output. The mixed production even for simultaneous operation is shown in the strip widths. The mixed production may be further availed of in lineal variation. The departure herein is with fifty-yard notation cycle for portions of the stock which carry no ten yard notation cycle.

This fifty-yard notation cycle drive, has corresponding to the gear 102, gear 110 in mesh with the gear 36 of the drum 12 (Figs. 1, 6). This gear 110 is provided with carrier 111 having shafts 112 carrying star wheels 113. Each of these shafts 112, herein shown as six in number, has thereon disks 114 anchored by keys 99 as to angular position, and as to longitudinal position by set screws 100. Each of these disks 114 is provided with seats 94 with bolts 96 holding plates 97 for anchoring the marketing type 93. The gear 110 and carrier 111 are mounted on shaft 115. Concentric with this shaft 115 and fixed with the frame 1, is disk

116 having tooth 117 of a width extent to coact with the star wheels 113 as in the overlapping position in the two planes transversely of the shaft 115. Here, as with the ten yard notation cycle, each rotation of the carrier is effective through the tooth 117 for advancing each of the shafts 114 a step position herein shown as one-seventeenth of a circumference for one-half yard notations. Accordingly, five of these sets of disks are complete as to the seventeen notations, and the sixth set of disks transversely is provided with sixteen notations leaving a blank between the fifty yard mark and the naught mark, one-half yard from each thereof to the omitted space making a total of one-yard overage so that there may be attaching region 107, cut region 108, and wrapping region 109, as extending from the fifty-yard portion, in the event the winding of the notation cycle be such as to show the residual yardage on the spool. If it be wound to show the yardage removed, of course the reverse of the use of this overage would occur.

Ten-yard signal marking.

In the rotation of the carrier 75, such carrier operates a speed reduction drive departing from the star wheel type of drives in the notation cycle printing or impression markers. In each rotation of the carrier 75, fixed eccentric 118 (Fig. 3) acts on eccentric strap 119 having pivotal connection 120 with arm 121 swinging on shaft 122 to throw such arm 121 radially of the shaft 61 as one throw in each rotation of the carrier 75. This arm 121, as pivoted on the bearing 120, has pawl 123, having ears 124, 125. Plunger 126 is normally thrust toward the pawl 123 by spring 127 in sleeve 128 swingably mounted on pivot 129. As the sleeve 128 is manually adjusted to be directed toward the ear 125, the plunger 126 is effective to rock the pawl 123 clear of ratchet 130, to thus throw this marker signal for the ten yard notation cycle out of gear. However, with the plunger 126 against the ear 124, the pawl 123 is held normally in engagement with the ratchet 130 and at each rotation of the carrier 75, there is a one-tooth feed of this ratchet wheel 130. At the recover stroke of this pawl 123, the ratchet wheel 130 is held by dog 131 yieldably held in engagement with this ratchet 130 against recover provided by spring 132. This ratchet wheel 130 is fast on the shaft 122 (Figs. 3, 4) which carries disk 133 having cam projection 134 effective in one-tooth position only of the rotation at the speed reduction of this shaft 122 for shifting shaft 135, as swingably mounted by link 136 from bearing 137 normally held against this cam 133, 134, by spring 138. This shaft 135 has

clamps 139 therealong adjustably mounting in desired transverse spacing, markers 74 for the ten-yard notation cycle carrying portions on the strip. As this cam portion 5 134, comes into position, it swings the marker 74 into active position for impress upon the strip material as passing about the drum 12 in the desired region of the notation cycle. If the notation cycle be 10 used in ascending sequence, it is desirable to have this signal a short distance before the completion of the cycle as a sense check for the operator. A marker 74 makes a visible impress upon the strip carrying the 15 notation legend. This signal marking is effected automatically at the desired location in the notation sequence slightly in advance of the terminus of the notation cycle. In practice, in the winding of strip material, as ribbons, the starting and intermediate speeds are run at a quite high lineal rate. As the desired yardage approaches completeness, this impress may be felt or observed, or both, by the operator who may 20 at once slack the speed and make the terminal cutting with a minimum loss of time and thus provide not only the automatic measuring of the ribbon, but the signal for having such occur more readily than 25 normal ribbon wrapping operations and independently of installing special measuring machines with the discrepancies coming therefrom as to the action of the ribbon.

35 *Fifty-yard signal marking.*

Adjacent the eccentric 118, about the shaft 61, but fixed with the frame 1, is minor eccentric 140 effective through eccentric strap 40 141 having pivotal connection 142 to rock arm 143 loosely mounted on shaft 144. This arm 143 carries pawl 123 coacting with ratchet 145 held against recovery by dog 131 held in position by spring 132. This ratchet 145 has proportionally an increased 45 number of teeth over the ratchet 130 to care for the fifty yard signal marking and is effective through shaft 144 having its disk 133 and cam projection 134 coacting with shaft 146 as carrying therealong a series of clamps 50 139 for positioning in the desired transverse position, markers 73. This shaft 146 is mounted by links 136 and is held against the cam 133, 134, by spring 138. Accordingly, in this carrier 75, there is this trans- 55 verse setting proportional to the fifty yard cycle an introduction to the desired transverse position of said strip portions as to the notation, these adjustably positioned signals which may be say in the region between 60 forty-nine and forty-nine and one-half yards. The marker 73 makes a visible impress upon the strip carrying the notation legend. This signal marking is effected automatically at the desired location in the no- 65 tation sequence. The functioning is auto-

matic. The purpose is the production of a device to supplement the notation which is disclosed by touch or sight inspection in helping the operator to increase the rate of handling strip material as to definite lengths 70 thereof.

Rotary cutters.

Split rings 147 are adjustably mounted along the cutter shafts 21, 22. These rings 75 147 may be independently adjusted by screws 148 (Figs. 1, 2, 9, 10). By operating the screw 148, its ring 147 is flexed as to weakening portion 148' to bring the ring into clamping position upon its shaft. Each of these 80 split rings 147 is provided with a shoulder 149 which has thereon knife 150 as held in position by ring 151 anchored by screws 152. Accordingly, the clamping screws 148 may serve to position a pair of knives as to each other 85 in the desired coacting adjustment, as well as position the pairs of knives along the shafts 21, 22, for the desired widths of strips and position of the cuttings whether to leave the notation cycle marginally or 90 centrally of such strips 25, 26.

Adjustable transmission to the receiver.

The drum shaft 44 is provided with pulley 153 about which extends belt 154 to pulley 155 (Fig. 11) on shaft 156 carrying pinion 157 in mesh with gear 158 on shaft 159. These shafts 156, and 159, are mounted with the frame 1. The shaft 159 is provided with worm 160 in mesh with worm wheel 100 161 on shaft 162 (Fig. 12) carrying ratchet wheel 163. Plates 164 on each side of this ratchet wheel 163 provide mounting for dog 165. From the plates 164 extends arm 166 to link 167 engaging arm 168 rockably 105 mounted in bearing 169 carried by the frame 1. Fixed with this arm 168 is arm 170 (Fig. 1) depending and carrying link 171. Upwardly extending from this link 171 is lever 172 having fulcrum 173 mounted 110 in bracket 174 fixed with the frame 1. Spring 175, from this fulcrum 173 takes up lost motion between the arm 170 and the lever 172. This lever 172 is forked and upwardly extends from the fulcrum 173 to 115 forks 176 at grooved collars 177 on shafts 178. These shafts 178, adjacent the grooved collars 177, carry friction wheels 179 simultaneously coacting with the opposite sides of disks 180 on shaft 181 carrying gear 182 in mesh with gears 183 and 184 on the shafts 27, 28, (Fig. 6). Accordingly, as the drum shaft 44 rotates, there is a speed reduction transmission control effective 120 through the angle lever 168, 170, for swinging the friction wheels 179 radially of the disks 180 which, as the stock is received on the shafts 27, 28, may be swung radially outward or away from the axis of the shaft 181, thereby reducing the speed of the shafts 130

- 27, 28. These shafts are driven by a direct transmission device at a continuous speed of rotation. Key rods 27, 28', hold the inner ends of the strips on these shafts.
- 5 The gear 41, on shaft 185, is fast with bevel gear 186 (Figs. 1, 5) in mesh with bevel pinion 187 fast on inner shafts 178. Pinion 188 on the outer shaft 178 is in mesh with pinion 189 on the inner shaft 178. Accordingly, these shafts 178 of each pair, are simultaneously oppositely rotated in causing the friction wheels 179 to engage the friction disks 180 for effecting rotation of such disks 180. These shafts 178 are provided with bearing blocks 190, 191, (Figs. 1, 5, 17) yieldably held toward each other by springs 192 thereby effecting a yieldable gripping action of the friction wheels 179 on the disks 180. These blocks 190, 191, 20 have bevel faces 193, toward each other, into which may be swung wedge 194 as mounted on bearing pin 195. This wedge 194 has extension handle 196. The friction wheels 179 are thus rotating while gripping the disks 180 to effect rotation of the disks. As the speed of the wheels 179 is constant, the position of the wheels as from the axis of the disks 180 varies the speed of such disks 180. The shorter radius gives higher angular velocity for the disks 180, and such is the speed used for starting the strips. As the diameter of the strip increases, the angular speed is gradually reduced. Accordingly, when it is desired to discontinue the 35 driving effectiveness of the friction wheels 179, it is only necessary to operate the handles 196 to bring the wedges 194 into position against the action of the springs 192 for thrusting the shafts 178 away from each other. The disks 180 are thus freed and if it be desired to reset the friction wheels for a repetition of this strip receiving operation, the pawl 165 is lifted and the variable speed control for the transmission is re-set.

45

Operation.

The bolt or roll of sheet material 5 has web 9 therefrom pass about the main drum 12 as given constant rotation drive. In 50 passing about this drum 12, the strip material receives printing impress from the active carrier as co-operating therewith. These notations in sequence may, for the lesser or ten yard cycle, be from the smaller 55 device or carrier 101, while for the larger fifty yard cycle as herein shown, the drive will be from the carrier 111. These carriers have thereon the plurality of printing elements which are inked, and in the speed 60 ratio as herein disclosed come into registry at the succession of intervals for the lineal spacing along the wide strip 9 of the sheet material as passing about the drum 12. In such travel of the material, there is a supplemental signal marking occurring at the 65 selected location in the cycle before the cycle is to terminate. This signal is by contact of the material as about the drum 12 effected by the action of a marker 73 or 74, according to the marking cycle as ten or fifty yards. This speed reduction drive for the signal markers is mounted on shaft 61. The material as thus given the lineal cycles, has the signal ready to pass from this drum 12. The complex or involved ratio of the marker 75 spacings on the type carrying members is a feature of importance herein in that there is clearance between the successive cycles of the marking say in the ten yard between ten and zero, and in the fifty yard cycle between 80 the fifty of one to the zero of the next cycle. This slight surplus of strip material affords an overage to anchor with a spool at the inner side, as well as a shielding wrapping for the stock at the outer side, and may be 85 used in either or both relations. This gives the measuring strip an effectiveness, not only for its own anchoring, but for the supplementing of wrapping.

The material as so marked as to notation 90 cycles and signals, is shown as passing from the drum 12, past blotting rollers 19, 20, and through the slitter knives 150. At this point, the stock is severed longitudinally into the individual notation strips of the desired widths. These strips are spaced after 95 passing the slitter and the guide rolls 23, 24. In this spacing, alternate reaches of the strip material are directed to diverge, one set to be anchored by rod 28' for wrapping about the shaft 28, while the alternate strips are anchored by rod 27' as to the free ends thereof for wrapping about the shaft 27. The smaller diameter at starting of the 100 wrapping requires a relatively high angular speed for these shafts, and the friction drive thereof by the friction wheels 179 coacting with the disks 180, has such drive effective near the shaft 181 on starting. As this drive continues, the wheels 179 are drawn 105 gradually outward by the linkage 172, 171, 170, therefrom driven by the pawl speed reduction device for gradually decreasing angular speed. As the desired diameter of tape is attained on these shafts 110 27, 28, or the supply roll 5 is exhausted, such rolls of the printed strip material may be removed, and the shafts 27, 28, recharged for a repetition of the cycle of operations. To begin such cycle it is in order to have 115 the friction wheels 179 against the inward smaller radius portions of the disks 180. This may be quickly accomplished by spacing the wheels 179 from each other by the throw-out device of the disclosure herein. 120 Handle 196 may be operated to force the wedge 194 in thus thrusting the shafts 178 away from each other against the resistance of the spring 192. As these wheels 179 are 125 thus cleared from contact with the disk 180, 130

the linkage may be released by pulling the pawl or dog 165 out of engagement with the ratchet 163. The wheels 179 are thus released so that against the resistance of spring 175, these wheels may be brought to the desired short radius position, and the handle 196 reoperated to withdraw the wedge 194 and thus allow the spring 192 to come into action in clamping the wheels 179 into engaging position with the disk 180 so that the spring 175 may not be effective in retracting.

What is claimed and it is desired to secure by United States Letters Patent is:

1. A machine for handling strip material comprising a mounting for a supply roll, an adjustable clamp for said roll, a guide for material from said roll, a drum for receiving material from the guide, an actuator for rotating said drum to withdraw the material from the supply roll as retarded by the clamp, a roll angularly spaced about said drum from the guide and coacting with the material as in surface contact with the drum to hold the strip material from crowding ahead of the drum, guide rolls for directing the sheet material as passing from the drum, a pair of shafts transversely of the material, driving means for the shafts, rotary knives in pairs on said shafts, guide means oppositely directing adjacent strips from the knives, shafts for receiving the strips, a variable speed friction drive for the shafts, transmission means from the actuator to said drive connection means from the transmission varying the speed of the shafts from the drive, there being a throw-out in the transmission operable to free the shafts and drive, and a control for releasing the drive for resetting.

2. For independent annular series of marking carrying elements and assembling means for positioning each element separately in predetermined angularly spaced relation of the elements in the annular series thereof, the combination of a machine for handling strip material comprising a drum, an actuator for rotating said drum, a carrier parallel to said drum, means effecting rotation of the carrier in synchronism with the drum, a shaft, and means independently anchoring said annular series of elements in marking angular alignment fixed angular relation as to said shaft, said shaft being parallel to the axis of the carrier and mounted by the carrier.

3. For independent annular series of marking carrying elements and assembling means for positioning each element separately in determined relation of the elements in the annular series thereof, the combination of a machine for handling strip material comprising a drum, an actuator for rotating said drum, a carrier parallel to said drum, means effecting rotation of the

carrier in synchronism with the drum, a shaft, means independently anchoring said annular series of elements in marking angular alignment fixed angular relation as to said shaft, said shaft being parallel to the axis of the carrier and mounted by the carrier, and an intermittent actuator in synchronism with the drum for positioning an axially extending grouping of said aligned marking elements of different series as to the drum.

4. A machine for handling strip material comprising a drum, an actuator operable relatively to the material acted upon, said actuator being effective for rotating said drum in synchronism with the travel of the strip material as a loop section over the drum for effecting lineal measurement of the material by the drum, a carrier parallel to said drum, transmission means effecting rotation of the carrier in synchronism with the drum, a shaft parallel to the axis of the carrier and mounted thereby, a marker exterior of the drum, and means eccentric of the drum movable relatively to the material for radially shifting said marker toward the drum in effecting marking action on the material.

5. A machine for handling strip material comprising a drum, an actuator operable relatively to the material acted upon, said actuator being effective for rotating said drum in synchronism with the travel of the strip material as a loop section over the drum for effecting lineal measurement of the material by the drum, a carrier parallel to said drum, transmission means effecting rotation of the carrier in synchronism with the drum, a shaft parallel to the axis of the carrier and mounted thereby, a marker exterior of the drum, fractional rotary shifting means movable relatively to the material for the marker as to the drum, and control means eccentric of the drum for radially shifting the marker toward the drum in effecting marking action on the material.

6. A machine for handling strip material comprising a drum, an actuator for rotating said drum, a carrier parallel to said drum, and notation-providing cycle means having intermission between successive cycles.

7. A machine for handling strip material comprising a drum, an actuator for rotating said drum, a carrier parallel to said drum, notation-providing cycle means on said carrier, and a drive for the carrier coacting with the cycle means to space said cycles of notation.

8. A machine for handling strip material comprising a drum, an actuator for rotating said drum, a carrier parallel to said drum, lineal sequence notation cycle marking means on said carrier for marking the material from said drum, and driving means for the carrier coacting with the marking

means for effecting a spacing between the initiation of one cycle and the completion of the preceding cycle.

9. For disks, a plurality of markers, and 5 means independently anchoring the separate markers in assembly with said disks, the combination of a machine for handling strip material comprising a drum, an actuator for rotating said drum, a carrier parallel to said drum, a shaft on the carrier, and 10 predetermined angular alignment means separately anchoring said disks on said shaft.

10. For disks having a peripheral series 15 of radially extending seats, a plurality of type, and means independently clamping said separate type in said separate seats, the combination of a machine for handling strip material comprising a drum, an actuator 20 for rotating said drum, a carrier parallel to said drum, a shaft on the carrier, and predetermined angular alignment means separately anchoring said disks on said shaft.

11. A machine for handling strip material 25 comprising guide means, a slitter for forming strip material, a drive for the material to the slitter, a speed reduction transmission from said drive embodying a variable speed device including a pair of rotary members, a shaft for receiving the slit material as 30 actuated by said transmission, connection means from the transmission progressively varying the speed of the shaft from the device, a throw-out for the transmission effective for spacing said rotary members, and 35 a control to permit resetting independently of drive control thereof.

12. A machine for handling strip material 40 comprising guide means, a drive for the material through the machine, a speed reduction transmission from the drive embodying a variable speed device including a pair of rotary members, a shaft for receiving the material as actuated by said transmission, 45 connection means from the transmission progressively varying the speed of the shaft from the device, a throw-out for the transmission effective for spacing said rotary members, and a control to permit resetting independently of drive control thereof.

13. A machine for handling strip material 50 comprising guide means, a drive for the material through the machine, a speed reduction transmission for the drive embodying a speed device including a friction disk, a friction wheel coating with the disk, connection means from the transmission 55 progressively varying the speed of the disk from the device, and a progressive control 60 throw-out for the transmission effective for spacing the wheel from the disk.

14. A machine for handling strip material 65 comprising guide means, a drive for

the material through the machine, a speed reduction transmission from the drive embodying a speed device including a pawl, connection means from the transmission progressively varying the speed of the pawl, a progressive throw-out for the transmission independently of said pawl, and a control to 70 permit resetting of the device.

15. A machine for handling strip material comprising guide means, a drive for the material through the machine, continuous travel speed reduction transmission from 75 the drive embodying a speed device including a pawl, connection means from the transmission progressively varying the speed of the pawl, a progressive throw-out for the transmission independently of said pawl, 80 and a control to permit resetting of the device.

16. A machine for handling strip material comprising guide means, a drive for the material through the machine, speed reduction transmission from the drive embodying a speed change device embodying a friction disk, a coating friction wheel, connection means from the transmission progressively varying the speed of the disk from 90 the device, a progressive control throw-out for spacing said friction wheel from the disk and additional control means for thereby rendering said wheel free for resetting radially as to the disk, and a shaft for receiving the material as actuated by said transmission.

17. A machine for handling strip material comprising guide means, a drive for the material through the machine, speed reduction transmission from the drive including a speed change device embodying a friction disk, a pair of coating friction wheels, connection means from the transmission progressively varying the speed of the disk from the device, a progressive travel throw-out for changing the spacing of the wheels to render the transmission ineffective, and additional control means for releasing the wheels for permitting ready resetting 110 as to the disk.

18. A machine for handling strip material comprising guide means, a drive for the material through the machine, speed transmission from the machine embodying a speed device including a pawl, connection means from the transmission progressively varying the speed of the pawl, a shaft for receiving material from the machine and as driven by said transmission, a progressive control 115 throw-out for the transmission independently of said pawl permitting resetting of the transmission upon release of the pawl.

In witness whereof I affix my signature.

ANDREW J. BOHNENGEL.
